UNITED STATES PATENT OFFICE.

JOHN F. BROWN, OF WEST WARWICK, RHODE ISLAND.

DESIGN FOR A HAT BUCKLE.

Application filed July 18, 1927. Serial No. 22,804. Term of patent 7 years.

To all whom it may concern:

Be it known that I, JOHN F. BROWN, a citizen of the United States of America, residing at West Warwick, in the county of Kent and State of Rhode Island, have invented a new, original, and ornamental Design for a Hat Buckle, of which the following is a specification, reference being had to the accompanying drawing, forming part hereof.

In the drawing:

Fig. 2 is an edge view of the same.

I claim:

The ornamental design for a hat buckle, as shown.

JOHN F. BROWN. [L.S.]
